UNITED STATES PATENT OFFICE.

CHARLES H. JANSEN, OF BROOKLYN, NEW YORK, ASSIGNOR TO SPEED KEY MANUFACTURING COMPANY, INC., A CORPORATION OF NEW YORK.

SPRING-KEY FOR TYPE-WRITERS.

1,293,105.

Specification of Letters Patent.

Patented Feb. 4, 1919.

Application filed April 8, 1918. Serial No. 227,303.

To all whom it may concern:

Be it known that I, CHARLES H. JANSEN, a citizen of the United States, and a resident of the borough of Brooklyn, city and State of New York, have invented certain new and useful Improvements in Spring-Keys for Type-Writers, of which the following is a specification.

The present invention relates to spring keys for typewriters. One object of my invention is to provide a spring key for typewriters which will be very inexpensive to manufacture and assemble, so that the device will compete favorably with other forms of keys. Another object of the invention is to provide a very compact key, one in which the top will be but slightly higher than the ordinary non-spring key which it is intended to replace. This is a decided advantage over the spring keys which extend up considerably above the ordinary key and require that extensions be applied to the space bar to bring it up according to the increased elevation of the key tops. With my improved key it is unnecessary to change the space bar.

Another object of my invention is to provide a spring key, the parts of which may be readily disassembled in order that the spring may be replaced if it should be broken.

Another object of my invention is to provide a very simple means for attaching the spring key to the type lever. Other advantages will be apparent from the detailed description hereinafter.

In the drawing forming part of this application,

Figure 1 is a plan view of my improved key attached to the typewriter lever,

Fig. 2 is a sectional view taken on the line 2—2 of Fig. 1,

Fig. 3 is a sectional view taken on the line 3—3 of Fig. 2,

Fig. 4 is a sectional view taken on the line 4—4 of Fig. 2,

Fig. 5 is an inverted plan view of the key attached to the lever,

Fig. 6 is a plan view of the top or cap and the bottom plate, and

Fig. 7 is a plan view of the cap alone.

I have shown the spring key 1 attached over the fixed top or plate 2 at the operative end of the type lever 3 of an ordinary type-writer.

The member which is directly secured to the top 2 consists of a ring 4 having a vertical wall surrounding the top 2. This ring has an inturned flange 5 around its upper edge, for a purpose which will appear, and it is provided with inturned projections 6 below, formed by indentations there being three projections indicated in the drawing. The ring 4 also has downwardly and inwardly turned clips 7 extending more than half way around the ring and these are intended to engage under the top or plate 2 for the purpose of holding the spring key in place. By having these clips extending somewhat more than half way around the ring the key may be attached to the top 2 by sliding it laterally thereover, the opposite clips 7' being sprung open by this action sufficiently to pass the center of the top 2, after which they spring back behind the top 2 and coöperate with the other clips in holding the key in place.

The cap or shell consists of the top portion 8, the depending flange 9 and the laterally and outwardly extending lugs 10. This cap forms a compartment or closure 11 for the key spring 12. The lugs 10 rest against the flange 5 of the ring when the cap is in its uppermost position, thus keeping the parts in operative relation so far as upward movement of the cap is concerned.

The bottom plate 13 is detachable and it is preferably depressed at the middle, as shown at 14 to provide maximum spring space. This plate may have apertures 15 to receive a suitable wrench or spanner by which the plate is turned to assemble or disassemble the parts of the key. The plate 13 is also provided with an upturned flange 16 which has as many slots or notches 17 as there are lugs 10 on the cap.

The spring, which may be of any form, is here shown as an ordinary S shaped spring 12 and it is held under compression between the cap and the plate 13. Any suitable covering may be applied to the cap, such, for instance, as a celluloid cover 18 having a letter or number 19 corresponding with the type bar which the key is to actuate. In assembling the key the cap is inserted into the ring 4 from the bottom upwardly, until the lugs 10 rest against the flange 5 of the ring. The spring 12 is then inserted within the hollow cap and the plate 13 is positioned so that the recesses 20 register with 110

the projections 6 of the ring. In this relation the plate may be inserted into the ring until it passes the projections 6, and when thus placed the plate places the spring under compression. While the plate 13 is pressed against the spring it is turned, as with a spanner engaging in the holes 15 and this will turn the plate so that the recesses 20 no longer register with the projections 6

10 and the plate is then locked above these projections. In this assembling operation the plate 13 is so positioned in relation to the cap that the lugs 10 on the latter enter into the slots 17 of the flange 16, as shown in

15 Fig. 6, so that both the plate and cap are turned together when the plate is being locked behind the projections 6. When the device is attached to the key lever the clips 7, 7' engage under the top 2 and hold the 20 key in place. The plate 13 rests on the top 2, the spring rests on the plate 13 and it presses upwardly on the cap, holding its lugs 10 against the flange 5. When the cap is struck by the finger, as shown in Fig. 2,

25 it is driven downwardly, further compressing the spring 12; and upon releasing the finger pressure the cap returns to its upper position again. The downward movement of the cap will generally be very slight in 30 actual operation. When the cap moves up or down its lugs 10 are free to move in the slots 17 of the plate 13, but the cap can not turn around to any great extent owing to the engagement of these lugs with the flange 16

35 of the plate. The edge of the lateral flange 5 of the ring acts as a guide all around the flange 9 of the cap and it steadies the cap so that it tends to move directly downwardly and upwardly.

40 If the spring 12 should be broken it is a very simple matter to replace it. To do so, it is only necessary to turn the plate 13 (after the key has been removed from the lever 3) until the recesses 20 register with 45 the projections 6, whereupon the plate may be lifted out of the ring. The broken parts of the spring are then removed, a new spring substituted for the broken one and the plate 13 is replaced and locked as before.

50 In this construction the parts are very economically made by stamping or drawing them by machinery, the assembling is very simple, and it is always an easy matter to 55 replace a broken spring at the place where the key is in use. The top of the key is but slightly higher than the top of the ordinary non-spring key, the parts are inclosed and there are no protrusions for the fingers to

60 engage.

Having described my invention, what I claim is:

1. A spring key for typewriters, including relatively movable members and a spring 65 adapted to be compressed between them, one

of said members comprising a hollow cap having a downwardly extending flange and an outwardly extending projection at the bottom of said flange, a ring surrounding said relatively movable members, an in-turned flange on said ring co-operating with the flange of said cap to guide the cap vertically and with which said outwardly extending projection of the cap co-operates to limit the upward movement of said cap. 75

2. A spring key for typewriters, including relatively movable members and a spring adapted to be compressed between them, one of said members comprising a cap having an outwardly extending projection, a ring 80 surrounding said relatively movable members and adapted to guide said cap, an in-turned flange on said ring with which the projection of said cap co-operates to limit the upward movement of the cap and spring 85 clips on said ring adapted to secure the spring key to a typewriter lever.

3. A spring key for typewriters, including relatively movable members and a spring adapted to be compressed between them, one 90 of said members comprising a cap having an outwardly extending projection, a ring surrounding said relatively movable members and provided with an in-turned flange with which the projection on the cap co-operates to limit the upward movement of the cap and an in-turned projection on said ring for holding said relatively movable members in said ring from below. 95

4. A spring key for typewriters comprising a ring having vertically spaced in-turned projections, relatively movable members including a cap, disposed in said ring and adapted to be held in place by the in-turned 100 projections of said ring and a spring arranged to be compressed between said relatively movable members.

5. A spring key for typewriters comprising a ring having an in-turned flange, relatively movable members in said ring, including a cap having an outwardly extending projection co-operating with said flange to limit the upward movement of the cap, lower in-turned projections on said ring, the lower 11 relatively movable member having peripheral recesses adapted to be registered with the lower projections of said ring, whereby said lower relatively movable member may be inserted beyond said lower projections and then turned to lock it in place, and a 1 spring arranged to be compressed between said relatively movable members.

6. A spring key for typewriters, comprising a ring having upper and lower abutment members extending inwardly, a cap having outwardly extending lugs adapted to engage said upper abutment member, a bottom plate insertible in said ring and having an upturned flange provided with recesses to receive the lugs of said cap, and a 1

spring arranged to be compressed between said cap and said bottom plate.

7. A spring key for typewriters, comprising a ring having means for securing it to the type lever, an inturned flange at the upper edge of the ring and inturned projections below said flange, a hollow cap having a depending flange and outwardly extending lugs at the bottom thereof, said ring flange being adapted to guide said cap vertically and coöperating with said lugs to limit the upward movement of the cap, a bottom plate having an upturned flange pro-

vided with slots to receive the lugs on said cap and having peripheral recesses adapted to be registered with said lower inturned projections on the ring, whereby said bottom plate may be entered beyond said latter projections and then turned to lock the bottom plate in said ring and a spring arranged to be compressed between said cap and said bottom plate.

Signed at the city, county, and State of New York, this 16th day of March, 1918.

CHAS. H. JANSEN.
